CLAIM

The ornamental design for sanding table for attachment to a garbage can, as shown and described.

DESCRIPTION

FIG. 1 shows a top view of a sanding table for attachment to a garbage can, according to the new design;

FIG. 2 is a top, front, side perspective view thereof;

FIG. 3 is a corner elevation view thereof, with the three other corners being a mirror image thereof;

FIG. 4 is a bottom plan view thereof;

FIG. 5 shows a top view of a second embodiment of a sanding table for attachment to a garbage can;

FIG. 6 is a top, front, side perspective view thereof;

FIG. 7 is a corner elevation view thereof, with the three other corners being a mirror image thereof;

FIG. 8 is a bottom view thereof;

FIG. 9 shows a top view of a third embodiment of a sanding table for attachment to a garbage can;

FIG. 10 is a top, front, side perspective view thereof;

FIG. 11 is a corner elevation view thereof, with the three other corners being a mirror image thereof; and,

FIG. 12 is a bottom view thereof.

The sanding table has a shape that allows a vacuum to be pulled through the holes in the top by vacuum(s) coupled to orifice(s) on the bottom of the sanding table. Thus, dust and debris may be pulled from the holes in the top and into coupled vacuum(s).

The broken lines, when present in the drawings, represent portions of the sanding table for attachment to a garbage can which form no part of the claim design.
